UNITED STATES PATENT OFFICE.

JOHN SCHERNER, OF MILWAUKEE, WISCONSIN, ASSIGNOR TO FEDERAL RUBBER MANUFACTURING COMPANY, OF CUDAHY, WISCONSIN, A CORPORATION OF WISCONSIN.

DESIGN FOR A MAT.

49,550.

Specification for Design.

Patented Aug. 22, 1916.

Application filed March 28, 1916. Serial No. 87,369. Term of patent 14 years.

To all whom it may concern:

Be it known that I, JOHN SCHERNER, a citizen of the United States, residing at Milwaukee, in the county of Milwaukee, State of Wisconsin, have invented a new, original, and ornamental Design for a Mat, of which the following is a specification, reference being had to the accompanying drawing, forming part thereof.

The figure is a plan view of a mat showing at the left hand side my new design.

I claim:

The ornamental design for a mat, as shown.

In witness whereof, I have hereunto signed my name in the presence of two subscribing witnesses.

JOHN SCHERNER.
